MECHANICAL TIME FUSE

André Varaud, Geneva, Switzerland

Application February 3, 1933, Serial No. 655,133
In Switzerland February 10, 1932

4 Claims. (Cl. 102—36)

The present invention relates to a mechanical time fuse of the type in which locking of the time regulating cap with the fuse body is automatically effected by the effect of the discharge.

5 Fuses of this kind have already been provided, in which a member integral with the cap moves in relation to the latter under the effect of inertia and at the moment of the firing, establishing by said movement a connection between the said cap and body of the fuse, which connection continues from the moment that it has been established. The members used for the connection are, for example, wedges or spikes, and their adjustment being effected for small accelerations, they very 10 often do not remain in position under the action of inertia resulting from the shocks of transport. These members are in fact most often kept in place by weak elastic members, which they quit by inertia at the moment of the firing or else 15 when a shock produced in the course of transport draws them away. The latter effect, which may be called an accident, but which has been observed in practice, has the great inconvenience of affecting the timing at the moment of em- 20 ployment.

The fuse according to the invention disposes of that inconvenience through the fact that it possesses a crown of ratchet or one-way teeth on the body of the fuse with which teeth co-operates 25 at least one plate or shoe movable in the axial direction in the adjustment ring, provided with corresponding teeth and so arranged that at the discharge of the shot it is caused by inertia to engage in the toothed crown, means being pro- 30 vided for this action to take place only during the linear acceleration and that the friction alone of the cap may maintain the adjustment during the trajectory of the projectile.

Thus the connection between the cap and the 35 body of the fuse is only produced at the moment of an acceleration, but does not continue when once said acceleration is ended. If therefore the fuse according to the invention is subjected to a shock during transport, it is quite possible that 40 such shock may in certain cases displace the shoe so as to bring it into contact with the toothed crown. But when once the effect of the shock is 45 terminated, the support will resume its original position in which it in no way opposes the timing 50 of the fuse.

At the moment of the firing and when once the linear acceleration is terminated, that is to say during the trajectory, the friction alone of the 55 cap on the body will suffice to maintain the adjustment, all the more as means can be provided

ensuring an invariably regular friction, as will be seen from the following description.

The drawing represents, by way of example, a fuse according to the invention.

Fig. 1 is an outer view of the fuse surmounted by the ring and a cap.

Fig. 2 is a vertical axial section of the fuse of Fig. 1.

Fig. 3 is a view from below of the adjustment ring, the upper half of this figure illustrating a modification and the lower half another modification of the said ring.

Fig. 4 is a view from above of the body only of the fuse.

Fig. 5 is a detail of the first modification, and 70

Fig. 6 is a detail of the second modification of Fig. 3.

Figs. 7 and 8 show an example of operation of the modification according to the detail of Fig. 5.

With reference to Fig. 1, the fuse body properly 75 so-called is represented at 1, at 2 is represented the adjustment ring mounted with friction upon it and at 3 the cap integral with the said adjustment ring.

These three members are seen in section in Fig. 80 2 which further shows, at 4, the movement on which the adjustment ring 2 acts by means of the arm 5, also visible in Fig. 3, said movement being partly removed.

The ring 2 is held on the body 1 by means of an 85 inner annular nut 6 and with interposition of a pressure ring 7, likewise visible in Fig. 4 where, in addition to the body 1, this ring together with the movement 4 seen from above are represented, the annular nut 6, the ring 2 and the cap 3 being 90 supposed to be removed. The ring 7 has two lugs 8 entering into corresponding notches 9 of the screw-thread 10 of the body 1.

Thus this ring 7 cannot rotate and consequently 95 cannot transmit to the annular nut 6 when once tightened, any angular movement capable of displacing it, that is to say of increasing or decreasing the effect of its tightening. Under this ring 7 is placed an elastic member 11 intended to exert a constant pressure on the adjustment ring 2 100 tightened by these members. This adjustment ring rests on the body with an air-tight joint 12 interposed.

The tightening obtained by the construction just described is secure from being put out of 105 order and suffices to maintain the adjustment of the ring during the whole duration of the trajectory. It is not, on the contrary, sufficient to hinder an angular displacement of the adjustment ring 2 and of the cap 3 through inertia of 110

rotation, when at the moment of discharge of the shot, the body 1 suddenly starts rotating at high speed according to the inclination of the rifling grooves.

5. For the purpose of establishing the connection necessary for preventing such an angular displacement in the direction contrary to the rotatory movement of the projectile, the body 1 is provided with a crown 13 having teeth of ratchet type directed against the surface of the ring 2. The ring 2 itself, as shown by the upper half of Fig. 3, has, seen from below, a certain number of recesses 14 irregularly pitched with regard to each other and inside which are situated plates 15 provided with teeth corresponding to those of the toothed crown. The irregularity of pitch of the recesses 14 is such that the teeth of the different plates 15 will have slightly different phase relationship with the teeth 13.

20. With reference to the upper half of Fig. 3, each toothed plate 15 is riveted to a small elastic blade 17 holding it hooked in the recess which is undercut for this purpose in the way shown in Figs. 5 and 7.

25. With reference to the lower half of Fig. 3, the toothed plates are kept in place by outer springs 18 placed in grooves of the ring 2 and bearing on the plates, each spring holding one end of two supports, as shown in Fig. 6. The method of fixing the toothed plates must be elastic to allow a certain axial displacement thereof so that at a given moment it can emerge a little from its recess and engage the toothed crown 13 of the body 1.

25. This is done, for example, in the manner shown in Fig. 8, when upon discharge of the shot the projectile is suddenly borne forward in the direction of the arrow 19 and the plate 15 through inertia does not immediately take part in this movement and, consequently, comes to engage the teeth of the crown 13 by slightly bending the elastic member, say the blade 17, which retains it. Rotary displacement of the ring 2 and body 1 is rendered impossible in the direction of the acceleration of the rotatory movement of the projectile, if care has been taken to place the teeth in the right direction. As long as this acceleration prevails the plate and the toothed crown remain in engagement and when once the acceleration is ended, these members become disengaged, which has then no detrimental effect.

By the irregular pitch of the toothed plates, it is assured that at least one of these plates will always lie in position to engage effectively the teeth of the crown at the instant of discharge.

It is clear that there can be any number of toothed plates, as well as of lugs of the ring 7,

also that the toothed crown may be integral with the body 1 or a separate member fitted thereto. What I claim as my invention and desire to secure by Letters Patent of the United States is:

1. A mechanical time fuse comprising a fuse body adapted to be secured to a projectile, a timing adjustment ring rotatable on the body, means ensuring constant frictional resistance to rotation of the ring on the body, toothed means operated by inertia when the projectile is subjected to an accelerating force of projection for positively engaging teeth on the body to lock the ring against rotation thereon during acceleration of the projectile, and spring means normally holding the toothed means inoperative, said spring means yielding under the inertia of the toothed means to render the toothed means operative.

2. A mechanical time fuse comprising a body adapted to be secured to a projectile and having a ring of one-way acting crown teeth, a timing adjustment ring rotatable on the body, means ensuring constant frictional resistance to rotation of the ring on the body, a plurality of plates with similar one-way acting teeth carried by the ring in alinement with the crown teeth of the body, and spring means normally holding the tooth plates out of engagement with the crown teeth but capable of yielding under inertia forces on said plates set up upon acceleration of the projectile to permit temporary and self-releasing engagement of said plates with said teeth.

3. A mechanical timing fuse according to claim 2, in which the toothed plates are irregularly pitched around the adjustment ring, the irregularities of pitch being determined to create phase differences of less than one tooth pitch in the engagement of different toothed plates with the crown teeth.

4. A mechanical timing fuse comprising a body adapted to be secured to a projectile and having a ring of one-way acting crown teeth, a timing adjustment ring rotatable in either direction on the body, means including a screw-tightened pressure ring for holding the adjustment ring on the body incapable of axial movement thereon but ensuring constant frictional resistance to rotation of the ring on the body, a plurality of toothed plates carried by the ring in alinement with the crown teeth of the body, and spring means normally holding the toothed plates out of engagement with the crown teeth but capable of yielding under inertia forces on said plates set up upon acceleration of the projectile to permit temporary and self-releasing engagement of said plates with said teeth.

ANDRÉ VARAUD.
